TRAVERSING MEANS FOR WINDING MACHINES

Application filed February 25, 1929. Serial No. 342,544.

This invention relates to machines for winding yarn, thread, wire or similar strand materials into a cop, cone, coil or package and has to do particularly with means for traversing the yarn lengthwise of the package to deposit it thereon in helical coils.

Winding machines for these purposes employed commercially at the present time are usually provided with a reciprocating or oscillating thread-guide which is operated by a cam or other mechanical movement. In this type of machine the direction of movement of the thread-guide and of the parts which operate it must be reversed as each end 15 of the yarn package is reached. At high speeds the reversal of the direction of movement of the thread-guide by the cam or other operating mechanism is so violent that it wracks and jars the machine and limits its 20 speed. At the present time winding machines of this type cannot be run at speeds much, if any, above 500 yards a minute, and it has not been considered practical to increase the speed of the machines.

25 It has also been proposed to employ a split drum to traverse the yarn, but for any except short yarn packages it is necessary to employ a drum of large bulk and weight.

Altogether, and as a result largely of the 30 difficulties mentioned, it has been considered impossible to increase the speed of winding machines to any substantial extent.

My invention entirely eliminates the use 35 of cams and oscillating elements and the mechanism for operating them, and does away with the shock, jar and wear resulting from sudden reversals of movement. The winding machine is much simpler, is less expensive to manufacture and has no reciprocating parts for traversing the yarn lengthwise of the package. As a result of my invention it is possible to run machines at double the present speeds, a thousand yards a minute being entirely practical, and at the 40 same time to produce an excellent package.

45 This result is accomplished by guiding the yarn onto the package by means of a traversing element, preferably a cylindrical roll, having a surface groove in the form of opposite crossing helices extending the length of

the roll, the roll being in contact or approximate contact with the yarn package, so that the yarn draws at a tangent to the traversing-roll and occupies only a small length of the guiding groove. As a result of this arrangement there is no perceptible friction or strain imposed on the yarn by the traversing means, and as the traversing element is of small diameter it can run at high speeds without vibration.

An important feature of the invention lies in the construction and arrangement of the grooves at the crossings to insure that the 55 yarn will be guided from one end of the package to the other and back again without being diverted from its direction of feed or travel at the crossings. This is a matter of great importance as it is usually desirable that the direction of feed shall not be reversed except at the ends of the package. This result is accomplished by forming the grooves 60 so that the bottom of one is at a different level from that of the other at the crossing, and chamfering the projecting point separating one groove from the other at the crossing. 65 When thus constructed the direction of feed is positively controlled even at extremely high speeds, and without increasing the tension on the yarn even if the point of yarn delivery is quite close to the traversing roll.

70 My invention is applicable to winding machines in which the coil or package is either frictionally driven or positively driven.

In the description of my invention and in the claims, I have used the term "yarn" to 75 designate the material which is to be wound whatever it may be, and the term "package" to designate the product formed by the machine. In the drawings, I have shown two embodiments of my invention, but I do not 80 limit myself to these, since the invention appears to be of a basic character which bids fair to revolutionize the winding art.

85 One object of the invention is to provide a traversing-means for winding machines 90 consisting in a single rotating element which may be operated at high speed with a minimum of power consumption.

95 Another object of the invention is to provide a traversing-means for winding ma- 100

chines which eliminates the use of bulky and heavy cams, while dispensing with the usual thread-guide and other reciprocating parts connected to be operated therefrom.

Another object of the invention is to provide a traversing-means constituted by a rotating roll or drum which serves the double purpose of driving the cop, cone or package by surface contact therewith while also actuating to feed the strand material thereon to traverse it longitudinally of the package.

Another object of the invention is to provide a traversing-means constituted by a rotating roll or drum of relatively small diameter which may be driven at high speed to increase the rate of production of the winding machine without the shock and vibration present in machines employing reciprocating thread-guides driven from cams.

Another object of the invention is to provide a traversing-means which operates on the thread, yarn or other strand material with less friction or abrasive action and which is adapted to control the reversal of the traverse of the strand more accurately and precisely to prevent overruns at the ends of the package.

Another object of the invention is to provide a traversing-means of the utmost simplicity, capable of being manufactured at low cost, and possessing greater durability in use.

Further objects of the improvement are set forth in the following specification which describes a preferred form of construction of the invention and several methods of applying it to use as illustrated by the accompanying drawings. In the drawings:

Fig. 1 is a front elevation of a portion of a winding machine, showing the winding-spindle and rotatable yarn-receiver on which the package is built in combination with the present improved traversing-means;

Fig. 2 is a plan view of the winding mechanism, showing the yarn-receiver as arranged to be driven from a rotating friction-drum or drive-roll and illustrating the traversing-means as embodied in a separate grooved roll;

Fig. 3 is an end elevation of the winding mechanism illustrated in Figs. 1 and 2;

Fig. 4 is an end elevation of a winding mechanism, showing a modified form of construction in which the package is driven directly from the grooved strand-traversing roll;

Fig. 5 is a view of the strand-traversing roll on the opposite side from that shown in Fig. 1;

Fig. 6 is an enlarged side view of the strand-traversing roll shown in a different position;

Fig. 7 is a similar enlarged view of the roll, illustrated in a position opposite to that shown in Fig. 6;

Fig. 8 is an angular cross-sectional view of the traverse-roll taken on line 8—8 of Fig. 7;

Fig. 9 is a similar sectional view taken on line 9—9 of Fig. 6;

Fig. 10 is a development of the surface of the strand-traversing roll;

Fig. 11 is a schematic view representing the profile of the bottom of the groove in the traverse-roll; and

Fig. 12 is an enlarged fragmentary sectional view of the roll taken on line 12—12 of Fig. 7.

The present drawings illustrate the invention as applied to use on so-called friction-drive or drum-driven winding machines in which the cop, cone or package is rotated through contact of its surface with the periphery of a cylindrical drive-roll or drum. It is to be understood, however, that the improved traversing-means forming the subject-matter of the present application may also be applied to use with winding machines of other types; for instance, in combination with a winding mechanism in which the cop, cone or package is wound on a positively-driven rotating spindle.

In Figs. 1, 2 and 3 of the drawings, 2 designates in general the main frame of a winding machine which comprises a plurality of winding units arranged in gang form along a bed or table 3. A series of cross-arm brackets 4 extend laterally of and are bolted at 6 to the longitudinal rails 7 of the bed 3, being provided with bearings for the horizontal driving shafts which operate the several winding mechanisms. As illustrated in Figs. 1 to 3, each bracket 4 is provided with mountings or housings 9 for annular ball-bearings 10 and 11, in which are journalled two parallel shafts 12 and 13. The rearward shaft 12 carries a series of cylindrical drive-rolls or drums 14, only one of which is illustrated in the different views. The forward shaft 13 carries a series of the grooved traverse-rolls 15, which serve as the means for feeding the yarn or other strand to and traversing it on the packages driven from the rolls 14. A similar pair of shafts are employed on the opposite side of the frame of the machine for carrying and driving the rolls which operate in connection with another series of winding units, but these parts are not illustrated in the present drawings as they are duplicates of the elements shown. The shafts 12 and 13 are rotated both in the same direction, as indicated by the arrows in Fig. 3, through the means of driving-mechanism located at the end of the machine, the drive being in accordance with any usual arrangement and therefore not herein shown or described.

Rising from the center of certain of the brackets 4 are uprights 16 formed with hubs 17, each of which supports a rod 18 held fast therein by a set-screw 19. Pivoted on the

rod 18 is a forked arm 20 held in place by a collar 21 abutting the side of its hub and fastened to the rod by a set-screw 22. At the outer end of the arm 20 is a bearing 23, in which is swiveled the cylindrical portion 24 of an auxiliary arm or extension 25. The arm 25 serves as a swinging support for the dead-spindle 26 on which the cop-tube or yarn-receiver is rotatably mounted to adapt 10 its surface to contact with the drive-roll 14 while permitting it to move away therefrom as the yarn-mass is built up thereon. As shown in the present drawings, the dead-spindle 26 is adapted to rotatively support a 15 tapered or conical cop-tube or yarn-receiver T on which the strand-material is wound in the form of a cone.

In winding conical masses of yarn the winding-spindle 26 is sometimes caused to 20 alter its inclination to the surface of the drive-roll to build the cone with an increasing degree of taper on its surface, and in such cases the arm 25 is permitted to turn in its bearing 23 on the arm 20 to provide for the 25 tilting action of the spindle. In other instances, the inclination of the spindle with respect to the drive-roll may remain constant, and where a cylindrical package is to be wound the spindle 26 is held in parallel relation with respect to the drive-roll 14. This is 30 accomplished by clamping the portion 24 of the arm 25 in the bearing 23, the latter being split for this purpose and provided with a binder-screw or bolt 27. The arrangement 35 of the cop-supporting means may be of the type shown or of any other suitable construction and the details of this part of the machine will therefore not be further described. Suffice it to state, that at the start of the 40 winding the surface of the cop-tube or yarn-receiver bears against the periphery of the drive-roll 14 and as the yarn-mass is built up to form the cop, cone or package the spindle recedes from the drive-roll to accommodate 45 the growth in the winding.

In the present arrangement of the winding mechanism as illustrated in Figs. 1, 2 and 3, the traverse-roll 15 is constructed of substantially the same diameter as the drive-roll 50 14 and is arranged in such relation thereto and with respect to the pivot on which the winding-spindle swings that the periphery of the mass being wound on the tube or receiver T will invariably bear a close relation 55 to the periphery of the traverse-roll.

That is to say, the periphery of the yarn-mass being wound will always be maintained adjacent to the surface of the traverse-roll 15, but without contact therewith.

60 The traverse-roll 15 which constitutes an essential feature of the present invention may be constructed from a cylinder of suitable metal, such as steel, and heat-treated or hardened to prevent undue wear on the sides of 65 its grooves. Preferably, it is formed in one

length and provided with relatively thin disks 30 of the same diameter as its body portion secured to its ends by means of screws 31. This construction provides that the groove in the periphery of the roll may be cut clear through the metal at its ends so as to allow clearance for the milling cutter or tool, and the disks 30 are afterward applied to position to form the end walls of the groove. The roll 15 may be secured fast on its shaft 13 by means of a 70 set-screw 32 or through any other suitable key connection.

It has been stated that the groove in the periphery of the roll 15 is continuous from one end to the other and back again in the reverse direction, but for convenience of description that part of the groove which extends in one direction will hereafter be referred to as one groove 35 and the other part 80 extending in the opposite direction as another groove 36. As herein shown, the two grooves 35 and 36 are of uniform lead or pitch, but in some cases they may have a variable pitch and the traverse-roll may be constructed with the 85 grooves having any desired number of convolutions about its axis. In the present illustration, each groove makes four turns or revolutions from one end to the other and there are consequently three crossing points on one side 90 of the roll and four on the reverse side, see 95 Figs. 1 and 5. With the grooves in the roll arranged as herein shown the yarn or other strand being guided and traversed therein will be caused to make four turns or convolutions around the surface of the cop-tube or 100 yarn-receiver at the start of the winding, assuming that the receiver is driven at the same rate of speed as the roll, but as the yarn-mass increases in diameter the cop or package will be rotated at a gradually diminishing speed 105 and consequently the strand will be laid with a correspondingly less number of turns in its traverse from one end of the package to the other. In Fig. 1 of the drawings, the cop or 110 cone is shown as starting with a four "wind", but in other instances the traverse-roll may have its grooves so disposed as to start the winding with a greater or less number of turns laid on the tube or yarn-receiver T.

The grooves in the surface of the traverse-roll 15 may be of suitable width to accommodate the largest size or thickness of yarn to be wound, or in other cases where there is a wide variance in the size of different kinds of material to be packaged different rolls may be employed having their grooves cut to the proper size. The two grooves 35 and 36 are of substantially uniform depth throughout a portion of their extent, but at the points where 115 they intersect the bottom profile of one groove 120 is raised and that of the other lowered, as shown most clearly in Figs. 8, 9 and 11, in accordance with the direction in which the strand travels in the groove. In other words, 125 one groove is lessened in depth and the other 130

groove is deepened, the purpose of this novel and ingenious arrangement being to prevent the strand from being diverted at the crossovers from the groove in which it is travelling in one direction to the groove extending in the opposite direction.

Referring to Figs. 6 and 7 of the drawings, which are enlarged views of the opposite sides of the traverse-roll 15, it will be noted that the 10 grooves 35 and 36 are bevelled off or chamfered on their sides at points beyond the crossovers, these chamfered portions being designated generally by the reference character 37 and their location described more specifically 15 hereinafter. It will be understood that when the strand travelling in one groove meets the other groove at the crossover there would be a tendency for it to catch on the point projecting toward the crossover so that it might 20 be diverted into the groove extending in the opposite direction and thus fail to be traversed throughout the whole length of one groove before being reversed to return in the other groove. It is to prevent such diversion 25 of the strand that the points at the crossovers are chamfered or beveled off as is more fully explained hereinafter.

In order to make clear the manner in which the strand follows through the grooves and 30 is traversed thereby from one end of the package to the other and back again, an explanation will now be given of the operation of the traverse-roll at the start of the winding.

In the embodiment of the invention as 35 shown in Figs. 1, 2 and 3, the drive-roll 14 and traverse-roll 15 turn in a clockwise direction, as viewed from the right-hand end, and therefore the cop-tube or yarn-receiver T will be rotated in the opposite direction 40 as indicated by the arrows in Fig. 3. The strand y of yarn, thread or other material is supplied from a suitable source, and drawing off therefrom is led through a suitable tension-device, not herein illustrated, usually arranged below and in front of the traverse-roll 15. The strand y leads from the tension-device to the traverse-roll 15 at a tangent to its periphery, and to start the winding it is simply laid across the surface 50 of the roll and its end attached to the cop-tube or yarn-receiver T. As shown in Fig. 1, the end of the strand y is coiled or wound around a groove t at the end of the receiver T to fasten it thereto.

To start the winding operation the arm 20 is swung down to place the surface of the cop-tube or yarn-receiver T in contact with the periphery of the drive-roll 14, and thereupon the receiver will be rotated from the roll to wind on the yarn. The drive-roll 14 and traverse-roll 15 are driven continuously and as the receiver T starts to rotate to take up the yarn the turning of the traverse-roll will cause the strand y to be en-

tered into one or the other of the grooves 35, 36 on its surface.

The strand y will thus be caused to follow the grooves from one end to the other and back again, and as it feeds therefrom at the top of the roll it is directed onto the cop-tube or yarn-receiver T to traverse it longitudinally thereof. Fig. 1 illustrates the roll 15 in position after the strand y has been traversed from the base end of the conical yarn-receiver T outwardly to its apex end, making four turns therearound, and reversed all this end and carried back with approximately three turns extending in the opposite direction. The winding operation continues 80 in this manner with the thread, yarn or other material feeding onto the cop-tube or yarn-receiver T in helical turns and building up in a conical mass as the axis of the package 85 recedes from the drive-roll 14 to accommodate the growth in the winding.

The method by which the strand is traversed and caused to follow each groove from end to end thereof without being diverted into the reverse groove at the crossovers will 90 now be explained in detail. For convenience of explanation let it be assumed that the strand y is drawing through the groove 35 at the right-hand end or starting point of this groove indicated at x in Fig. 6. As the roll 15 turns in the direction of feed of the strand the latter will follow the groove 35 from the point x in a direction toward the left. That part of the groove 35 extending from the point x to the first crossover a on 100 the opposite side of the roll 15 is of substantially one-half the maximum depth of the main portion of the groove, as indicated at 40 in Fig. 8. Slightly in advance of the first crossover a the bottom of the groove 105 35 rises, as shown at 41 in Fig. 8, until it is of relatively slight depth at 42. The purpose of this change in profile is to lift the strand in the groove 35 so that when it crosses the other groove 36 at the crossover 110 designated a in Fig. 7 it will not be diverted into the groove 36.

Beyond the crossover a the right-hand wall of the groove 35 is chamfered or beveled off as indicated at 37 to eliminate a sharp point 115 directed towards the path of travel of the strand in the groove. As the yarn y rides on the raised bottom surface 42 of the groove 35, see Fig. 8, it passes across the groove 36 above the chamfered edge of the latter so 120 that its direction of traverse is not influenced thereby. Beyond this point the groove 35 deepens again, as indicated by the dotted line 43 in Fig. 8, and continues at the full depth until the next crossover b on the opposite side of the roll is reached where it rises sharply in the incline 44 illustrated in Fig. 9. At this point the strand will again be raised toward the surface of the roll to cause it 125 to pass through the crossover b at the mini- 130

mum depth to prevent it from being diverted into the groove 36 which is of maximum depth at this point. The relation of the strand as it draws through the second crossover *b* is clearly shown by the dot-and-dash line in Fig. 9, it being understood that the strand is delineated slightly above the surface on which it rides to render the showing clearer.

10 Beyond the crossover *b* the profile of the groove 35 recedes from the surface of the roll again, as indicated by the dotted line 45 in Fig. 9, and continues at the maximum depth until a point slightly in advance of the crossover *c* is reached on the opposite side of the roll from the crossover *b*, see Fig. 7. At this point there is again an abrupt rise in the bottom of the groove, similar to the portion 44 shown in Fig. 9. At the crossover *c* the 15 strand again crosses on a high point and rides against the left-hand side of the groove 35, the right-hand wall of which is chamfered off in the manner as before explained to remove the sharp point directed toward the 20 crossover.

The next crossover *d* occurs at a point equidistant from the ends of the roll 15 and in this case the full depth of the groove 35 is maintained as indicated in Fig. 6. At this 25 location the other groove 36 has its left-hand wall chamfered off to eliminate the sharp point projecting toward the crossover. The groove 35 now continues at the maximum depth clear to its end, with the fifth crossover *e*, sixth crossover *f* and seventh crossover *g* of exactly the same form as described in connection with the central crossover *d*.

At the end of the roll the terminus of the groove 35 connects with the groove 36 and 30 at this point its depth is lessened so that the starting portion of the groove 36 leading back toward the right is the same as the starting portion of the groove 35, that is having a depth as indicated at 40 in Fig. 8. As the 35 strand travels back toward the opposite end of the roll 15 feeding through the groove 36 it is raised or lifted over the first groove 35 at the first crossover *g* to be recrossed in this direction. At this point the oppositely extending groove 35 is of maximum depth, as 40 before noted, and the strand crosses it at the upper level as explained in connection with the showing at 41 and 42 in Fig. 8. The groove 36 then deepens abruptly and continues at maximum depth to the next crossover *f* where its bottom has a sharp rise similar to the showing at 44 in Fig. 9, so that the strand once more passes through this crossover at the upper level. The groove 36 deepens again from this point on and is again 45 formed with an abrupt rise at the next crossover *e*. The formation of this crossover is identical with those previously described at *g* and *f*, and likewise the next crossover at *d* 50 is the same as regards the rise in the level of

the groove 36 where it crosses the groove 35. At the next crossover *c* the groove 36 retains its full depth as previously indicated and from there on the maximum depth is maintained through the crossovers *b* and *a*.

Referring more particularly to the graphic delineation of the profile of the bottom of the grooves 35 and 36 as presented in Fig. 11, a brief recapitulation of the description of the groove formation will now be given. 55 It will be observed from Fig. 11 that starting at the point *x* at the right-hand end of the roll 15 the groove 35 is of medium depth until it reaches a point in advance of the crossover *a* where its bottom is raised to the minimum depth. Beyond the crossover *a* it assumes the maximum depth again until the next crossover *b* is reached where it rises from maximum to minimum depth and then recedes again to maximum depth with the same rise and fall at the crossover *c*. From the crossover *c* the groove 35 continues at maximum depth through the crossovers *d*, *e*, *f* and *g* until it reaches a point just in advance of its connection at *z* with the returning groove 36 where its bottom rises to half-depth.

The reverse groove 36 starts at half-depth and continues thus to the crossing point *g* where its bottom rises to minimum depth, and then beyond this crossover is again depressed to the maximum. At the crossover *f* its profile is again raised and lowered, and the same at the crossovers *e* and *d*. Beyond this point its bottom is profiled at the maximum depth and continues at this level through the crossovers *c*, *b* and *a* to the point *x* where it is raised again to join the half-depth starting end of the groove 35.

It will be observed from the foregoing that through the peculiar and novel construction of the grooves in the traverse-roll 15 the strand is caused to be raised at certain points in travelling in one direction so as to prevent it from being diverted into the opposite groove which has the maximum depth. At other points the travel of the strand will be through those portions of the groove of maximum depth to prevent it from being diverted into the oppositely directed groove of less depth. In this way, the strand is caused to traverse in each direction to the full extent of each groove, whereby it is guided onto the package being wound in a series of helical turns which cross and recross each other and build up in layers forming the mass or body of the package.

In the modified form of construction of the winding mechanism illustrated in Fig. 4, the separate drive-roll is dispensed with by arranging the cop or package to be driven directly from the traverse-roll 50. This roll 50 may be identical in construction with the roll 15 previously described, having its grooves arranged in the same manner to

70

130

traverse the yarn back and forth on the package as the latter contacts with and is driven from the periphery of the roll. Other modifications may also be made in the construction 5 and arrangement of the parts of the winding mechanism without departing from the spirit and scope of the present invention.

It will be observed that the invention provides an extremely simple construction of 10 traversing-means for winding machines which may be driven at high speed with a minimum of power consumption and without jar or vibration of the moving parts.

The heavy and bulky cam employed in previous types of winding machines is eliminated and no reciprocating traverse-bars and thread-guides are required so that the mechanism is much less subject to wear and deterioration.

20 Since the present improved traversing-means comprises but one rotating element of relatively small diameter and little weight the momentum and inertia of heavy parts are avoided whereby an increased speed of operation of the machine may be effected with less shock and jar and less wear and tear on the parts.

By mounting the operating shaft for the traversing-roll in ball-bearings the machine 30 is rendered capable of high speed operation, while being particularly smooth-running and quiet in operation.

With the improved traversing-means of the present invention the winding machine is rendered more efficient in use with its productive capacity greatly increased and its operating parts are much less subject to wear and deterioration.

It has also been demonstrated that the present improved traversing-means operates with greater precision and uniformity to produce better winding without loose coils or overruns at the ends of the cop, cone or package.

It is to be observed that when the package 45 is driven by surface contact with the traversing-roll the yarn guided in the grooves of the roll will have a lineal speed slightly greater than the peripheral speed of that portion of the groove with which the yarn is in contact.

50 The roll will thus have a tendency to apply a certain degree of drag or tension on the yarn as it feeds to the package. Therefore the usual tension device may be dispensed with in some cases and the roll itself depended upon for applying the required amount of tension to the yarn during the winding of the package. This feature is of

55 special advantage in handling soft yarns having only a slight twist since the tension is applied at or near the point where the strand is laid on the package and therefore there will be less chance of stretching or pulling apart the fibers of the yarn as is the case where the tension is applied at some distance from the 60 point of winding.

While a preferred form of construction of the invention with one modification in the arrangement of the parts is herein shown and described by way of example, it is to be understood that the invention is not limited 70 to the present embodiment.

I claim:

1. A yarn-traversing device for winding machines comprising a rotating element having on its peripheral surface a groove in 75 which the yarn is received and by which it is guided, said groove being in the form of opposite crossing helices, the point of one projection between opposite portions of the groove at a crossing being chamfered to insure the yarn being guided in a predetermined direction.

2. A traversing-means for winding machines comprising a rotatable roll having its periphery provided with a strand receiving 85 and guiding groove extending in helical convolutions in one direction and back in the opposite direction with its convolutions crossing each other, the points on the surface of the roll where the convolutions of the groove 90 cross being chamfered off to prevent the strand as it travels in one direction in the groove from being diverted into the oppositely extending portion of the groove.

3. A traversing-means for winding machines comprising a roll having its periphery provided with a continuous groove extending helically in one direction and back in the opposite direction, with portions of different depth at the crossing points, and with 100 portions of the edges of the groove chamfered off to remove the sharp points directed toward the crossovers.

4. A strand-traversing device for winding machines comprising a rotating element having on its peripheral surface a strand receiving and guiding groove consisting of crossing and connecting helices, and means at a crossing point to control the passage of the 105 yarn through the crossing.

5. A strand-traversing device for winding machines comprising a rotating element having on its peripheral surface a strand receiving and guiding groove consisting of oppositely extending crossing helices, and means 115 at a crossing point to control the direction of the yarn at the crossing.

6. A strand-traversing device for winding machines comprising a rotating element having on its peripheral surface a strand receiving and guiding groove consisting of crossing and connecting helices, and means at a crossing point to maintain the strand in that portion of the groove in which it is traveling and prevent it being diverted into the other portion 120 of the groove.

7. A strand-traversing device for winding machines comprising a rotating element having on its peripheral surface a strand receiving and guiding groove consisting of crossing 125

and connecting helices, and means constructed in the roll at a crossing point to maintain the strand in that portion of the groove in which it is traveling and prevent it being diverted into the other portion of the groove.

5 8. A traversing-means for winding machines comprising a rotating element having on its peripheral surface a strand receiving and guiding groove consisting of opposite 10 crossing helices, a portion of the groove at a crossing being deeper than the opposite portion of the groove at the crossing, and means at a crossing to prevent the strand being diverted from the direction in which

15 it is traveling.

9. A traversing-means for winding machines comprising a rotating element having on its peripheral surface a strand receiving and guiding groove extending helically in 20 one direction and back in the opposite direction with its convolutions crossing and with the major portion of the groove of substantially uniform depth except at a crossing where that portion of the groove extending in 25 one direction is of less depth than the portion of the groove extending in the opposite direction.

10. A strand-traversing device for winding machines comprising a rotating element 30 having on its peripheral surface a strand receiving and guiding groove consisting of oppositely extending crossing helices with a portion of the groove at a crossing cut away on its edge to prevent the strand as it travels 35 in one direction in the groove being diverted into the oppositely extending portion of the groove.

In testimony whereof I hereunto affix my signature.
